UNITED STATES PATENT OFFICE.

WILLIAM FULLER HOSFORD, OF OAK PARK, ILLINOIS, ASSIGNOR TO WESTERN ELECTRIC COMPANY, INCORPORATED, OF NEW YORK, N. Y., A CORPORATION OF NEW YORK.

METHOD OF COATING STRANDS.

Application filed October 11, 1924. Serial No. 743,159.

This invention relates to a method of coating strands, and more particularly to a method of forming a coating which is common to a plurality of strands.

5 An object of the invention is to provide an improved method of forming a common coating for a plurality of strands, one of which is twisted around another.

The improved method may be employed 10 to great advantage to produce an article described in my copending application, Serial No. 743,160, filed October 11, 1924, which article comprises a plurality of spaced electrical conductors in strand form having a 15 common coating of pulpos material attached to the conductors by an intermingling of the fibers thereof, one of the conductors being twisted around another in accordance with the practice usually followed 20 in the manufacture of telephone cables and the like. However, the invention is limited to such use only in so far as pointed out in the appended claims.

In one specific embodiment of the invention, a plurality of spaced electrical conductors in strand form are simultaneously subjected to a liquid containing pulp in such manner that a ribbon of wet pulp is applied 25 to the conductors. This ribbon is formed into a substantially dry, uniform coating 30 common to the conductors which are subsequently twisted around each other, the coating being adapted to remain unbroken during the twisting operation.

35 In another specific embodiment of the invention, a ribbon of wet pulp is applied in the manner above described to a plurality of spaced electrical conductors in strand form and is so treated that it becomes a uniform coating common to the conductors. 40 While the coating is still in a moist condition, the conductors are twisted around each other, after which the coating is thoroughly dried.

45 The word "pulp" as used in the specification and claims is to be understood as defining and including any cohering fibrous mass whether suspended in a liquid, moist, or substantially dry.

50 Other objects and features of the invention

will become apparent as the detailed description progresses, reference being had to the accompanying drawings, wherein—

Figs. 1 to 2 are complementary parts of a plan sectional view taken through apparatus 55 by which the improved method may be practiced;

Figs. 3 and 4 are complementary views of a longitudinal section taken through the apparatus shown in Figs. 1 and 2;

Fig. 5 is a sectional view taken on line 5—5 of Fig. 4;

Fig. 6 is a sectional view taken on line 6—6 of Fig. 1;

Figs. 7 to 10 inclusive are enlarged transverse views which progressively illustrate the manner in which the apparatus shown in Figs. 1 to 6 inclusive forms a common coating of pulpos material upon a plurality of electrical conductors in strand form;

Fig. 11 is a fragmentary longitudinal view of a plurality of electrical conductors having a coating formed by the apparatus shown in Figs. 1 to 6 inclusive;

Fig. 12 is a longitudinal sectional view 75 through apparatus which may be employed to practice another embodiment of the invention, and

Figs. 13 and 14 are sectional views taken on lines 13—13 and 14—14, respectively, of 80 Fig. 12.

It is believed that a complete understanding of the improved method will be procured from a description of the apparatus by means of which the method may be practiced.

The apparatus shown in the accompanying drawings is adapted to apply a common coating of paper or other pulpos material to a plurality of electrical conductors in strand form and to twist the conductors 90 around each other, the coated and twisted conductors constituting the aforementioned article described in my copending application, Serial No. 743,160, filed October 11, 1924.

The apparatus first subjects the electrical conductors to a liquid containing pulp in such manner that a ribbon of wet pulp is deposited upon the conductors. Excess moisture is removed from the ribbon which 100

is formed into a uniform coating for the conductors, the conductors being subsequently twisted around each other.

That portion of the apparatus which applies the pulp to the conductors and forms it into a uniform coating upon the conductors is substantially identical with the apparatus shown and described in the co-pending application of J. S. Little, Serial No. 734,874, filed August 29, 1924. This apparatus comprises a drum 16 partly submerged in a liquid which contains pulp and is held in a tank 17. The drum 16 comprises an annular foraminous portion 27 through which liquid may flow from the tank 17 into the drum 16, the liquid being discharged through the ends of the drum. The tank is supplied with liquid containing pulp from a mixing vat (not shown).

As best shown in Figs. 2, 4, and 5, electrical conductors 12 which are to be subjected to the liquid containing pulp are withdrawn from a plurality of supply reels 65 and are guided by a plurality of grooved rollers 70 to the foraminous portion 27. The grooved rollers 70 are adapted to space the conductors 12 a predetermined distance apart and in this instance are adapted to guide two conductors traveling in the direction of the arrows to the foraminous portion. A ribbon 73 of wet pulpy material is applied to the conductors as they are carried through the tank 17 by the drum 16, the drum being driven by means hereinafter described. The arrangement is such that some pulp is first strained onto the foraminous portion 27 before the conductors are brought into contact therewith. Then when the conductors contact with the initial layer of pulp on the foraminous portion and the drum continues to revolve in the tank 17, an additional amount of pulp will be deposited on the conductors and on the foraminous portion. It will be noted that the ribbon 73 is common to the spaced conductors 12 (Fig. 7).

A woven belt 75 aids in freeing the pulp ribbons from the foraminous portion 27 when the conductors 12 leave the drum 16. The belt 75 is held in contact with the drum 16 by a felt covered roller 76 which coacts with the belt 75 and the drum 16 to squeeze excess liquid from the pulpy material adhering to the conductors. The conductors 12 and the ribbon 73 are advanced with the belt 75 and between it and a similar belt 79. The belt 75 is trained over a plurality of rollers 80 and 81 and over a plurality of rolls 83. Means (not shown) is provided for driving the roller 80 and it drives the belt 75 which in turn frictionally engages and drives the drum 16 and the belt 79, the belt 79 being held in contact with the belt 75 by rubber covered rollers 85 and 86. The belts 75 and 79 together with the rollers 80,

81, 85, and 86 prevent the pulp ribbon 73 from losing the form imparted to it by the felt covered roller 76 and the drum 16, the form so imparted to the ribbon being illustrated in Fig. 8.

A forming mechanism 90 receives the conductors 12 and the ribbon 73 attached thereto when they leave the belts 75 and 79, the conductors and the ribbon being guided to the forming mechanism by a sheave 95. The forming mechanism 90 is preferably of the type shown and described in the co-pending application of H. W. Jesperson, Serial No. 713,704, filed May 16, 1924. The forming mechanism 90 is actuated by means indicated at 92 and is adapted to wrap the ribbon 73 around itself and around the conductors to form a uniform homogeneous coating common to the conductors. The manner in which the ribbon is wrapped around itself and the conductors is illustrated in Fig. 9, the fully formed coating being designated by the reference character 13 in Fig. 10.

The forming mechanism 90 draws the conductors 12 toward each other during the wrapping operation so that a quantity of fibrous pulp will be compressed and clamped between the conductors. This pulp, when dried, serves to insulate the conductors from each other.

In one embodiment of the invention, the coated conductors pass directly from the forming mechanism 90 to a housing 100, the sheave 101 being provided to guide the coated conductors into the housing. Means indicated at 106 is provided in the housing 100 for subjecting the pulpy coating on the conductor to air of predetermined relative humidity and predetermined temperature. This means is described in detail in the co-pending application of J. S. Little, Serial No. 716,842, filed May 30, 1924. When the coated conductors 12 pass from the housing 100 a sheave 115 guides them to a take-up reel 109.

The take-up reel 109 is removably mounted upon a shaft 117 which is rotatably journaled intermediate its ends in a bracket 118 (Figs. 1 and 6). The reel 109 is splined to the shaft 117, and is held in place upon the shaft by a washer 119 and a nut 120. A bevel gear 122 splined to the shaft 117 meshes with a bevel gear 123 secured to a shaft 124 rotatably journaled in the bracket 118. A pinion 125 secured to the shaft 124 meshes with a gear 126 which is rigidly secured to a bracket 127 mounted on a frame 128. The bracket 118 is rigidly secured to one end of a shaft 120 journaled in the bracket 127, a pulley 131 being secured to the other end of the shaft. The pulley 131 may be rotated by a belt 132 which connects the pulley with any suitable driving means (not shown).

A friction disc 134 secured to the bevel gear 122 engages a friction disc 135 secured to a collar 136 splined upon the shaft 117. Disposed around the shaft 117 is a compression spring 138 which has one of its ends resting against the collar 136 and the other of its ends resting against a washer 140 secured to the shaft 117 by a nut 141. The spring 138 yieldingly urges the friction disc 135 into engagement with the friction disc 134.

It is obvious that when the pulley 131 is driven by the belt 132, the reel 109 will rotate around the axis of the shaft 117 and will also rotate around the axis of the shaft 130. The coated conductors passing from the housing 100 will be wound upon the reel and will be twisted around each other in the manner illustrated in Fig. 11, thus producing the article described in my aforementioned copending application, Serial No. 743,160, filed October 11, 1924.

In another embodiment of the invention the coated cores are twisted around each other, directly after they pass from the forming mechanism 90, by a twisting mechanism 150 interposed between the forming mechanism 90 and the sleeve 101 (Fig. 12). A sheave 151 guides the coated conductors to the twisting mechanism 150 which comprises a plurality of gripping members 153, each of which is pivotally mounted intermediate its ends upon one end of a tube 154 adapted to accommodate the coated strands. One end of each gripping member 153 is adapted to engage the coating 13 on the cores 12 and the other end thereof is provided with an anti-friction roller 155. Springs 156 yieldingly urge the gripping members 153 into positions wherein the rollers 155 rest upon a grooved collar 158 slidably journaled upon the tube 154. Longitudinal displacement of the grooved collar 158 relative to the tube 154 is limited by an annular flange 160 formed integral with the tube 154 and a set collar 161 mounted on the tube. A slide 163 rotatably journals the tube 154 and is mounted upon rods 165 which are in turn mounted in brackets 166. The tube 154 is held against longitudinal displacement relative to the slide 163 by a gear 168 keyed to the tube and a set collar 169 mounted upon the tube. The gear 168 meshes with a gear 170 splined upon a shaft 171 which is rotatably journaled in brackets 172. The gear 170 is secured to the slide 163 by a split collar 173 which permits the gear to be rotated by the shaft 171, but constrains the gear to travel with the slide 163 when the slide moves in either direction along the rods 165. Secured to the shaft 171 is a pulley 175 which is operatively connected to any suitable driving means (not shown) by a belt 176.

Slidably mounted on the rods 165 is a yoke

180 carrying anti-friction rollers 181 which ride in the groove of the collar 158. Pivotally secured to the yoke 180 by a pin 183 is a rack 184 slidably journaled in a bracket 185. A segment 186 which meshes with the rack 184 is pivotally mounted upon a pin 187 and is formed integral with a segment 188 which meshes with a rack 190 slidably journaled in a bracket 191. Secured to one end of the rack 190 is an anti-friction roller 192 riding in a cam slot 193 of a cam 194. The cam 194 is adapted to reciprocate the rack 190 so that it will oscillate the segments 188 and 186 to reciprocate the rack 184. The rack 184, when reciprocated, will reciprocate the collar 158 along the longitudinal axis of the tube 154. The collar 158 will in turn reciprocate the tube 154, but through a lesser distance because of the lost motion connection between the collar and the tube. The cam 194 is driven by any suitable means (not shown) in such manner that when the tube 154 is advanced in the direction in which the coated conductors are being advanced, the tube and conductors will travel at substantially the same rate of speed. It is obvious that when the tube 154 is being advanced in this direction, the collar 158 will bear upon the anti-friction rollers 155 and cause the gripping members 153 to seize the coated conductors. The shaft 171 which is driven by means of the pulley 175 and the belt 176 causes the gear 170 to drive the gear 168 which in turn rotates the tube 154. Therefore when the gripping members 153 seize the coating 13 and travel with the coated conductors and the coating, the gripping members 153 will be rotated around the longitudinal axis of the tube 154 and will twist certain portions of the conductors 12 around each other, the portions which are so twisted being the portions disposed intermediate the sheaves 101 and 151. Of course, the conductors 12 will be twisted in opposite directions from the gripping members 153 so that each conductor will comprise a plurality of sections twisted in one direction and a plurality of positions twisted in the other direction.

In the latter embodiment of the invention, the coating 13 is relatively moist during the twisting operation, the coating being subsequently dried in the housing 100. When the coated cores pass from the housing 100 the sheaves 108 and 115 are adapted to guide them to a take-up reel (not shown) and which is driven by any suitable means (not shown).

What is claimed is:

1. A method of coating strands, consisting in applying a common, continuous, integral and substantially homogeneous coating to a plurality of strands, and twisting one strand around another.

2. A method of coating cores, consisting

- in applying a common, contiguous, integral and substantially homogeneous coating to a plurality of spaced strands, and twisting one strand around another.
5. A method of coating strands, consisting in applying a common, continuous, integral and substantially homogeneous coating of pulpous material to a plurality of spaced strands, and twisting one of the strands around another.
10. 4. A method of coating strands, consisting in subjecting a plurality of spaced strands to liquid containing pulp in such manner that pulp is applied thereto, forming the pulpous material into a common coating for the strands, and twisting one of the strands around another.
15. 5. A method of coating strands, consisting in subjecting a plurality of spaced strands to liquid containing pulp in such manner that pulp is applied thereto, removing excess moisture from the pulp applied to the strands, forming the pulp into a common coating for the strands, and twisting one of the strands around another.
20. 6. A method of coating strands, consisting in applying pulp fibers to a plurality of spaced strands in such manner that the pulp is attached to the strands solely by an intermingling of the fibers thereof, forming the pulp into a common coating for the strands, and twisting one of the strands around another.
25. 7. A method of coating strands, consisting in subjecting a plurality of spaced strands to liquid containing pulp in such manner that pulp is applied thereto, causing relative lateral motion between the strands and a portion of the applied pulp so that it is firmly attached to the strands to form a common covering therefor, and twisting one of the strands around another.
30. 8. A method of coating strands, consisting in applying a ribbon of wet pulp to a plurality of spaced strands, fabricating the ribbon into a uniform coating common to the strands, and twisting one of the strands around another.
35. 9. A method of coating strands, consisting in applying a ribbon of wet pulp to a plurality of spaced strands, removing excess moisture from the ribbon, forming the ribbon into a common covering for the strands, and twisting one of the strands around another.
40. 10. A method of coating strands, which consists in applying a ribbon of wet pulp to a plurality of spaced strands, wrapping the pulp around the strands to cause an intermingling of the fibers thereof, and twisting one of the strands around another.
45. 11. A method of coating strands, consisting in applying unfinished paper to a plurality of spaced strands, subsequently completing the fabrication of the paper on the strands in such manner that the paper is formed into a common covering therefor, and twisting one of the strands around another.
50. 12. A method of coating strands, consisting in applying unfinished paper to a plurality of spaced strands, wrapping the unfinished paper around the strands to form a common covering therefor, and twisting one of the strands around another.
55. 13. A method of coating strands, consisting in applying unfinished paper to a plurality of spaced strands, wrapping the unfinished paper around the strands to form a uniform covering common to both of the strands, and twisting one of the strands around another.
60. 14. A method of coating strands, consisting in applying moist pulp to a plurality of spaced strands in such manner that it holds the strand in spaced relation, fabricating the pulp into a uniform covering common to both of the strands, and twisting one of the strands around the other.
65. 15. A method of coating strands, consisting in embedding a plurality of spaced strands in a ribbon of pulp, wrapping the ribbon around the strands, and twisting one of the strands around another.
70. 16. A method of coating strands, consisting in embedding a plurality of strands in a ribbon of pulp adapted to hold the strands in spaced relation, forming the ribbon into a uniform coating common to the strands, and twisting one of the strands around another.
75. 17. A method of coating strands, consisting in applying wet pulp to a plurality of continuously moving spaced strands in such manner as to cause the strands to be covered with a quantity of pulp, forming the pulp into a common coating for the strands, and twisting one of the strands around another.
80. 18. A method of coating strands, consisting in applying moist pulp to a plurality of strands to form a common coating therefor, drying the pulp, and then twisting one of the strands around another.
85. 19. A method of coating strands, consisting in applying moist pulp to a plurality of spaced strands, forming the pulp into a uniform coating common to the strands, drying the coating, and then twisting one of the strands around another.
90. 20. A method of coating strands, consisting in applying a common coating to a plurality of strands, and simultaneously twisting and coiling the coated strands.
95. 21. A method of coating strands, consisting in applying unfinished paper to strands held in spaced relation, forming the unfinished paper on the strands to constitute a

continuous and integral coating therefor, and twisting the strands one around the other.

22. A method of coating strands, consisting in applying unfinished paper to strands held in spaced relation, fabricating the unfinished paper and forming it into a coating

for the strands, and twisting the strands one around the other.

In witness whereof, I hereunto subscribe my name this 29th day of September A. D., 1924.

WILLIAM FULLER HOSFORD.
